US00D516855S

(12) **United States Design Patent** (10) Patent No.: **US D516,855 S**
Akamatsu et al. (45) Date of Patent: **** Mar. 14, 2006**

(54) **PILLOW**

(75) Inventors: **Masao Akamatsu**, Anjo (JP); **Atsuhiko Itakura**, Anjo (JP); **Takenori Kusakabe**, Anjo (JP)

(73) Assignee: **Inoac Corporation**, Aichi (JP)

(**) Term: **14 Years**

(21) Appl. No.: **29/228,042**

(22) Filed: **Apr. 20, 2005**

Related U.S. Application Data

(62) Division of application No. 29/201,253, filed on Mar. 12, 2004, now Pat. No. Des. 507,142.
